UNITED STATES PATENT OFFICE.

ARTHUR C. BAUMWART, OF OSSIAN, IOWA.

FARM-GATE.

SPECIFICATION forming part of Letters Patent No. 363,108, dated May 17, 1887.

Application filed February 23, 1887. Serial No. 228,548. (No model.)

To all whom it may concern:

Be it known that I, ARTHUR C. BAUMWART, of Ossian, in the county of Winneshiek and State of Iowa, have invented a new and useful Improvement in Farm-Gates, of which the following is a full, clear, and exact description.

My invention relates to gates, and has for its object improvements in the construction and operation of the same, which will enable them to be as readily opened and closed by a person upon horseback or seated in a wagon as when upon foot.

Reference is to be had to the accompanying drawing, forming part of this specification, the figure shown being a perspective view of my improved gate, its supports, and operating mechanism, said gate being slightly elevated.

The gate *a* is pivoted at one end, between and near the bases of posts *b*, upon a pin, *a'*. At either side of said posts, in line with and a short distance from them, rise standards *c*. Bars *d* connect said posts and standards, and their axes turn in sockets provided therein. Arms *e*, having eyes *f* on their extremities, extend diagonally outward from said arms in the direction of the gate. From the rear of said bars extend parallel arms *g*, connected by cross-bars *h* and, carrying between them weights or weighted boxes *g'*, which counter-balance the weight of the gate. From the front of said bars *d* extend levers *h* and braces *h'*. On the upper faces of the bars *d* stand supports *i*, upon which rest stay-rods *j*, the ends of which are respectively attached to the braces *h* and cross-bars *h*. Stay-rods *j* connect the braces *h* and arms *e*. Between or upon the ends of the levers *h* is held a wheel or flanged roller, *k*. Pulleys *l* are located at or in the tops of the standards *c*, pulleys *l'* are swiveled to their inner sides, and levers *m* are pivoted to said standards and extend outwardly therefrom toward either side of the gate. Cords *n* pass over the pulleys *l* and *l'*, being connected at either end to the levers *m* and arms *e*. Cords *n'* are connected to the levers *m* at their extremities.

o is a post, against which the end of the gate rests when it is closed.

On drawing down one of the levers *m* by its cord *n'* the cord *n* slips over the pulleys *l* and *l'* and draws the arm *e* outward and backward, causing the bar *d* to turn backward and out-

ward. As said arm *d* turns, its arms *g*, bearing the weighted box *g'*, are carried downward and inward toward the heel of the gate, and its lever *h*, with brace *h'*, is carried upward and outward toward the head of the adjacent post *b*. Simultaneously therewith the other bar *d* turns outward and backward, its arm *e* passes backward and outward, its arms *g*, bearing the weighted box *g'*, are carried downward and inward toward the heel of the gate, and its lever *h*, with brace *h'*, is carried upward and outward toward the head of the other post *b*, the other cord *n* slipping over the other pulleys *l* and allowing the other lever *m* to fall correspondingly with the one which was drawn down. Said levers as they rise elevate the gate and carry the wheel *k* toward its end post. As the gate is raised by said levers its heel turns upon the pin *a'*, said gate passes outward and backward between the posts *b*, and the weighted boxes *g'* pass downward and inward at either side of said posts and come to rest below the plane of the heel of the gate and inward toward the roadway, causing said gate to stand at an acute angle with the roadway and have its center of gravity outside and beyond its heel and the roadway, the arms *e* on the bars *d* then extending diagonally outward from said bars, and the levers *m* being raised, as before the gate was opened. By giving a quick sudden pull to the other cord *n'*, its lever *m* acts through its cord *n* to draw the adjacent arm *e* inward and forward, said arm causes its bar *d* to turn forward and inward, the other bar *d* and arm *e* take the same course, the gate turns inward and forward on its pivot *a'* between the posts *b*, the arms *g* and weighted boxes *g'* rise, the levers *h* fall and draw the wheel *k* backward, the center of gravity of the gate is transferred to the other side of its heel and within the roadway, and said gate then falls by its own weight across the roadway against the post *o*, the levers *m* rising again, as before the gate was closed, and the arms *e* standing diagonally inward from the bars *d*.

The pivoting and supporting of said gate between the posts *b* and the supporting its outer end upon the wheel *k* on the levers *h* give a steady and uniform movement to the gate in its rise and fall and prevent it from wavering.

The cords n' are within the reach of a person on horseback or in a wagon, as well as of one upon foot, enabling said gate to be quickly raised or lowered without the necessity of dismounting from the horse or leaving the wagon.

By raising the pin a' to a higher hole in the posts b , thus elevating the heel of the gate, said gate may be more easily opened and closed during the winter season, when snow covers the ground.

Having thus fully described my invention, what I claim as new, and desire to secure by Letters Patent, is—

1. The gate a , having a flanged roller, k , between its rails and supported by the posts b , and the levers h , to which said flanged roller is journaled, in combination with the bars d , arms e g , weights g' , cords n n' , pulleys l l' , levers m , and standards c , substantially as shown and described.

2. The combination of the standards c , levers m , cords n n' , pulleys l l' , arms e , and bars d with the levers h , posts b , and gate a , having a wheel, k , between its rails, substantially as shown and described.

3. The combination, with the posts b and the gate a , pivoted at the lower inner corner between said posts, of the post c , the bar d , journaled in the posts b c and provided with the lever h , the roller k , journaled in the end 30 of the lever h and engaging the gate, the weighted arm g , the lever m , cord n , and pulleys l l' , substantially as shown and described.

ARTHUR C. BAUMWART.
